[57] CLAIM

The ornamental design for combined bottle and bowl package, as shown and described.

DESCRIPTION

FIG. 1 is a perspective view of a combined bottle and bowl package showing our new design;
FIG. 2 is a top plan view thereof;
FIG. 3 is a right side elevational view, the left side elevational view being a mirror image thereof;
FIG. 4 is a front elevational view, the rear elevational view being a mirror image thereof;
FIG. 5 is a bottom plan view thereof;
FIG. 6 is a reduced perspective view of the bottle shown separate for clarity of illustration;
FIG. 7 is a bottom plan view thereof;
FIG. 8 is a front elevational view thereof;
FIG. 9 is a rear elevational view thereof;
FIG. 10 is a left side view thereof;
FIG. 11 is a right side view thereof; and,
FIG. 12 is a bottom plan view thereof.
